François René Marcel, Brooklyn, N. Y.

Application October 27, 1937, Serial No. 171,222

7 Claims. (Cl. 132—18)

This invention relates to the treatment of hair and more particularly to novel devices for cleansing, protecting and improving the condition of hair on the human head.

5 Objects and advantages of the invention will be set forth in part hereinafter and in part will be obvious herefrom, or may be learned by practice with the invention, the same being realized and attained by means of the instrumentalities and 10 combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

Of the drawings:

20 Fig. 1 is a plan view of a hair-treating comb embodying a preferred form of the invention;

Fig. 2 is a plan view of a razor illustrating a modified embodiment of the invention;

25 Figs. 3, 4, 5 and 6 are sections taken on Fig. 1 as indicated by the respective section lines;

Fig. 7 is a rear plan of the device shown in Fig. 1 with a razor attachment thereon;

Fig. 8 is a section on line 8—8 of Fig. 7; and 30 Fig. 9 is a perspective of the razor guard shown in Figs. 7 and 8.

As to the subject matter of Fig. 2, disclosed but not claimed in my copending application Ser. No. 9,535, filed March 6, 1935, this application is a continuation in part.

35 One object of the invention is to provide for removing foreign matter from the surfaces of individual hairs on the human head. It has been found that the hair surfaces become incrusted with dirt, oil, grease, soap and other foreign matter which ultimately forms a relatively hard casing about the hair shaft and in and around the microscopic scales which make up the outer covering of the hair. Furthermore this surface coating of the hair forms a lodging for many 40 different types of microbes and bacteria which ultimately enter into the interior structure of the hair, causing it to split or be harmed or destroyed. Also the bacteria which thus gain access to the interior of the hair may thence pass 45 into the scalp and body of the person so affected. Ordinary shampooing or treatment of the hair with the usual solvents and tonics has been found ineffective to remove the foreign matter and bacteria which become intimately coated and 50 hardened on the hair as described.

The present invention provides a mode of dislodging and removing such foreign matter including microbe and bacteria growths, in a very simple and effective manner, and without harming the hair or the individual in any way. The 5 removal of such matter not only cleanses and purifies the hair but it greatly improves the health and luster of the individual hairs and of the head of hair as a whole. Hair which before treatment was stiff, dull and lifeless becomes 10 softer and more alive to the eye and touch. Furthermore the hair is frequently improved and conditioned for further treatments. For example the ability of hair to acquire a permanent wave is frequently greatly improved by previous treatment 15 in accordance with the invention.

In essence, the invention comprises subjecting individual hairs, preferably a large number simultaneously, to a surface scraping action starting near the scalp and working outward toward 20 the ends. This surface scraping is preferably performed by an edged instrument which will quickly and thoroughly dislodge and largely remove the surface coating of foreign matter on the hair. The scraping action may be performed 25 upon the hair when dry or the hair may be first wetted or softened by the application of a suitable lotion or other softening and/or solvent agent. In more extended application of the treatment the hair may be scraped both with and 30 without the application of the solvent or softening agent as hereinafter described in detail.

Another object of the invention is to provide 35 novel and useful means for carrying out the hair treatment above described. I have found that the scraping of the hair surfaces may be effectively and rapidly performed by drawing individual hairs between the opposed edges of sharpened scraping tools similar to knife or razor edges and my invention comprises providing in simple mechanical form a device by which this scraping 40 action may be performed simultaneously and successively upon a great many hairs so that the entire head of hair of an individual may be quickly and effectively treated.

45 Other objects of the invention comprise providing a hair cutting means which may optionally be used in combination with the scraping and cleansing action of the invention.

It will be understood that the foregoing general description and the following detailed description as well are exemplary and explanatory of the invention but are not restrictive thereof.

Referring now in detail to the present preferred embodiment of the invention illustrated by 55

way of example in the accompanying drawings, Fig. 1 shows a hair scraping device in the form of a comb. As shown the comb is formed of an integral piece of hard tool steel capable of taking and holding an edge similar to razor or knife steel although other substances capable of taking a sharp edge, such as glass or metal alloys may be used. The piece of steel forming the comb is generally triangular in cross section, but having rounded edges as shown. The back 10 thereof is flat and substantially at right angles to the top edge 11, while the plane of the front edge 12 forms substantially the hypothenuse of a right triangle with the sides 10 and 11. Approximately 15 half of the piece of steel is reduced, rounded and tapered to form a convenient handle 13, while the remaining portion is constructed generally like a comb having teeth 15, the points of which lie along the narrow or lower edge 14 in the piece 20 of steel. Each tooth 15 is bevelled in opposite directions downwardly from the surface 12 so as to form sharp cutting edges 20 along both sides of the tooth. Each tooth is also tapered longitudinally from a relatively narrow point to a somewhat wider base where it merges with the upper solid portion of the piece of steel. The bevelling between two adjacent teeth is carried back for a considerable distance into the piece 25 of steel beyond the sharpened junction 21 between the tooth proper and the rear face 10 of the comb. Thus a tapered groove 22 of diminishing width and depth extends backwardly into the body of the comb from the sharpened edge 21. The method of forming the bevelling and groove 30 between two adjacent teeth is diagrammatically indicated in Fig. 3, the cutting tool being indicated by the circular member 23. Thus the space between two adjacent teeth forms a V-shaped notch, the bottom edges 20 of which are of razor 35 sharpness, while the apex 21 of the V-groove is preferably no wider than a single average human hair and may be somewhat narrower.

The length of the V-shaped grooves between the teeth may be uniform throughout the comb 40 or, as shown in Fig. 1, the grooves may be of 45 two or more different lengths whereby to give a shingling effect on the hair when the comb is used as a hair cutting tool. For purposes of scraping and cleaning hairs, however, it has been found that a uniform length of groove between 50 the teeth is entirely effective. The method of cutting the deeper grooves 22a by a somewhat larger cutting disc 23a is indicated in Fig. 4.

In carrying out the treatment of hair in accordance with the use of the device, the grooved 55 face 12 of the comb is laid against the individual scalp with the flat back 10 outward and the comb drawn along the scalp in the direction of the growth of the hair, so that all the hairs on the 60 head pass along the edges 20 of the teeth and into the notches 21. Thus there is a drawing and scraping action of the cutting edges 20 and 21 on the individual hair and a great deal of foreign matter is removed and loosened from the 65 surfaces of the hair as previously described. Dead hairs and split ends will also be removed by this operation. When the comb is first passed through untreated hair considerable resistance 70 will be encountered due to the coated matter on the hairs, but after several applications of the comb it will be found that it passes through the cleaned hairs much more readily. The combing action should be repeated until the comb comes 75 through the hair practically free of foreign matter.

After all the hair on the head has been subjected to a thorough scraping action, as described, a further cleansing action may be effected by subjecting the hair to the softening and solvent action of a suitable tonic or lotion 5 which will tend to dissolve and soften foreign matter which has been loosened by the dry scraping operation, but which still clings onto or about the hair. After application of such lotion, the scraping comb should be again drawn through 10 the hair one or more times to remove the matter which has been acted upon by the lotion. A lotion which I have found suitable for this purpose is a solution containing a hair softening agent such as glycol, together with an alcohol 15 miscible in oil as softener and solvent, together with a suitable germicide or antiseptic, but the invention is not limited to this particular solution, as other known hair lotions and tonics containing suitable solvents and hair softening 20 agents may be used.

Upon completion of the foregoing operations, the hair is preferably shampooed and then combed or subjected to any further hairdressing 25 operation as may be desired.

In Fig. 2 is shown a modified form of hair scraping and cutting device, originally disclosed in my copending application Ser. No. 9,535 filed March 6, 1935. As shown, a razor blade 50 is provided with teeth having cutting edges 51, 52 30 and 53 of respectively shorter lengths. A suitable guard member 60 may be provided below the razor blade itself, said guard member having projecting teeth with upturned fingers 61 to cover the ends of the long teeth 51. Suitable means, such as a frame member 62 of a common type, may be provided for attaching the razor blade and guard frame to handle 63.

In operation, the hair-cutting razor described, is adapted to cut hair of varying lengths, such 40 as the three lengths shown, simply by moving the serrated blade through the hair. The hairs are not only cut of varying lengths at any particular line of cutting movement, but also the hairs may be individually tapered or cut on a bias due 45 to the fact that they fall into the cutting notches and are thus cut on either side to a tapered point. While primarily designed for cutting or shingling hair, this construction also serves to scrape the surfaces of the hairs which are drawn 50 between the sharpened edges of the blades and into the edged notches. Thus the scraping action may be combined with a cutting or shingling operation of the hair.

Another form of means for combining a shingling or hair cutting action with the scraping comb mechanism shown in Fig. 1 is disclosed in Figs. 7, 8 and 9. As shown, a hair cutting 55 razor blade 70 may be detachably mounted on the rear face 10 of the comb, a retaining groove 60 71 being formed in the back of the comb for seating a blade-holding bracket 72. A suitable blade-holding guard 73 of resilient material such as spring steel is adapted to spring over the top edge of the comb and press together the comb 65 and razor blade as shown in Figs. 7 and 8.

The invention in its broader aspects is not limited to the specific mechanisms shown and described but departures may be made therefrom within the scope of the accompanying claims 70 without departing from the principles of the invention and without sacrificing its chief advantages.

What I claim is:

1. In a device for treating hair the combina- 75

tion of a pair of beveled, sharpened edges converging to form a V-shaped groove of a minimum width less than that of a human hair.

5. 2. In a device for treating hair the combination of a pair of beveled, sharpened edges converging to form a relatively deep V-shaped groove of a minimum width less than that of a human hair.

10. 3. A device for treating hair comprising a comb with teeth tapering in width from the back of the comb toward their ends, the edges of said teeth being sharpened to a cutting edge.

15. 4. A device for treating hair comprising a comb with teeth tapering in width from the back of the comb toward their ends, the edges of said teeth being sharpened to a cutting edge and the space between said edge diminishing to form a groove no wider than a human hair.

5. A device for treating hair comprising a comb with steel teeth tapering in width from the back of the comb toward their ends, the edges of said teeth being sharpened to a cutting edge.

6. 5. A device for treating hair comprising a comb with beveled teeth tapering in width from the back of the comb toward their ends, the edges of said teeth being sharpened to a cutting edge.

7. 10. A device for treating hair comprising a comb with beveled teeth tapering in width from the back of the comb toward their ends, the edges of said teeth being sharpened to a cutting edge and the space between said edges diminishing to form a groove no wider than a 15 human hair.

FRANÇOIS RENÉ MARCEL.
